DESIGN FOR A HANDBAG

Maurice J. Kruger, New York, N. Y., assignor to Kruger-Ressner, Inc., New York, N. Y., a corporation of New York

Application November 6, 1946, Serial No. 134,559

Term of patent 7 years

(Cl. D87—3)

To all whom it may concern:

Be it known that I, Maurice J. Kruger, a citizen of the United States, residing at New York city, in the county of New York and State of New York, have invented a new, original, and ornamental Design for a Handbag, of which the following is a specification, reference being had to the accompanying drawing, forming part thereof.

In the drawing

Fig. 1 is a side elevational view of a handbag, showing my new design; the opposite side thereof being identical;

Fig. 2 is a front elevational view, the opposite side thereof being identical except for the location of the pull knobs; and

Fig. 3 is a side elevational view, the bag being shown in open position.

I claim:

The ornamental design for a handbag, substantially as shown and described.

MAURICE J. KRUGER.
